UNITED STATES PATENT OFFICE.

ROBERT C. MATHES, OF WYOMING, NEW JERSEY, ASSIGNOR TO WESTERN ELECTRIC COMPANY, INCORPORATED, OF NEW YORK, N. Y., A CORPORATION OF NEW YORK.

ELECTRIC WAVE TRANSMISSION.

Application filed September 1, 1925. Serial No. 53,777.

- This invention relates to electric wave transmission, for instance over circuits having distributed therealong a plurality of so called voice operated or voice pointed repeater sets or other translating devices, and aims to efficiently control such devices in a prearranged manner from different points, such as the opposite ends of the circuits, and to improve the operation of voice operated repeater sets and systems employing them, especially with regard to avoiding confusion in case two talkers at opposite ends of a circuit having such sets in tandem therein start talking at nearly the same time.
15. A voice operated repeater set transmits voice currents or like transmission efficiently in only one direction at a time, and is controlled by the transmission to insure that the set is conditioned for efficiently repeating in the proper direction, in order to provide for two way repeating. The system specifically described hereinafter and shown in the drawing as embodying one form of the present invention has such sets in tandem in a circuit, and in order to obtain efficient through or overall transmission in one direction over the circuit the tandem connected sets must all transmit efficiently in that direction at the same time. Consequently the 25 problem arises of determining the control of the circuit when two talkers at its opposite ends start talking at nearly the same time. The first talker should control the circuit and in accordance with this form of the invention, whichever one's talk reaches the central repeater first is given complete control of the circuit.
- To accomplish this operation, the system employs an auxiliary control circuit, in addition to the talking circuits, the use of the auxiliary circuit generally being preferable to carrying control current on the talking conductors in the frequency range outside of the essential range of the voice currents or 40 the like. Sources of control current of distinctive frequencies are provided at the terminal repeater stations. The system is so arranged that, when voice energy is introduced into either terminal station for transmission to the other terminal station no attempt being made to transmit in both directions at the same time, a fraction of the voice current energy is employed for (1) causing control current energy of given frequency to be sent from the terminal repeater station nearest the speaker, over the control circuit, to each of the through repeater stations, located between the terminal repeaters, to condition the through repeaters for efficient transmission toward the terminal repeater 55 distant from the speaker, and (2) causing the repeater set at the near terminal repeater station to be conditioned for efficient transmission toward the distant terminal station. The voice current energy which is to be 60 transmitted to the distant station is passed through a transmission delay circuit or path in the near terminal repeater set before being transmitted from the set, the delay thus introduced in the transmission of this part 65 of the voice current energy not only facilitating the operation just mentioned of conditioning the near terminal repeater for efficient transmission without loss of transmission due to the time required for such conditioning but further, resulting in the control energy sent along the control circuit arriving at each of the repeater stations which it is to control, before the speech energy, 70 circuits of equal grade or speed preferably 75 being used for transmitting the speech current and the control impulses between stations since the delay obtained by the delay circuit avoids any necessity for employing higher propagation speed for the control energy than for the speech energy, between 80 the stations. The delay introduced by the delay circuit is made such that the first syllable, in traversing the talking conductors, will be thus preceded at each through 85 repeater station by the control current on the control circuit, by a time sufficient for the control current to condition the repeater set at that station for efficient transmission 90 toward the terminal station distant from the speaker before the syllable arrives at that through repeater station. Consequently, mutilation of the beginnings of words is prevented. Preferably, the condition of the repeaters for efficient transmission in the desired direction is accomplished by switching 95 means. Considering, now, the condition that first syllables of speech are almost simultaneously transmitted from each terminal station toward the other, the system is so 100 arranged that the control frequency which is 105

first to arrive at the center repeater station will operate equipment at that point which will prevent the other control frequency from passing that repeater and thus from reversing the pointing of the repeater sets already pointed by the first frequency. This first frequency will, however, proceed beyond the center repeater and reset any repeaters there which may have been set by the second frequency.

Other features and objects of the invention will appear from the following description of the invention taken in connection with the accompanying drawings, wherein Figs. 1 to 5, placed side by side in numerical order from left to right, show a system embodying a form of the invention.

In that system, a control line 1, for transmitting the control currents referred to above, is made to serve a number of talking circuits by the assignment of control frequencies, two for each talking circuit, the circuits for transmitting the control currents being generally similar to the carrier current circuits in the well known grouped frequency system of carrier current telegraphy.

Three talking lines or circuits are shown, designated 2, 3, and 4 respectively, and placed on the drawing one above the other in numerical order from the bottom of the drawing up, line 2 with its repeater sets R_1 to R_5 being shown below the dash line 5—5, line 3 with its repeater sets R_6 to R_{10} being shown between the dash line 5—5 and the dash line 6—6, line 4 with its repeater sets R_{11} to R_{15} being shown between the dash line 6—6 and the dash line 7—7 and the control line 1, with repeater sets R_{16} to R_{18} for repeating the control currents, being shown above the dash line 7—7. Each one of the systems is shown as having five repeater stations, one constituting each figure of the drawing. The stations constituting Figs. 1 and 5 are terminal stations and will be referred to as the west terminal station and east terminal station, respectively; the station constituting Fig. 3 is the center repeater station, and the stations constituting Figs. 2 and 4 will be referred to as intermediate repeater stations, being located intermediate the center station and a terminal station. The two terminal stations are shown alike, except that they are symmetrically reversed, and except that they are arranged to generate and receive different control frequencies. The two intermediate stations are also shown alike, except that they are symmetrically reversed with respect to each other. Each of the five repeater stations comprises three two-way, voice pointed, telephone repeater sets, one set in each talking line; and, moreover, the center station and the intermediate stations comprise a two-way control current repeater each, in-line 1, for repeating the control currents referred to above. Cer-

tain of the telephone repeaters are of the so called biased type and the others are of the so called neutral type. These types are distinguished in that, after a period of transmission in the repeater circuit, the biased repeater is left in condition to transmit efficiently in the line circuit only in the direction in which it last transmitted, until transmission in the other direction over the circuit is initiated, whereas, after such a period of transmission the neutral repeater will not efficiently transmit in either direction until new transmission takes place conditioning the circuit to transmit efficiently in the line circuit only in the direction of transmission. The circuit of line 2 will be referred to as of the neutral type, since its voice operated repeaters are all of the neutral type. The circuit of line 3 will be referred to as of neutral-biased type, its terminal repeaters being of the neutral type while its other repeaters are of the biased type. The circuit of line 4 will be referred to as of biased type, since all of its repeaters are of the biased type. It will be understood that ordinarily the repeater stations are considerable distances apart. It will also be understood that although only one intermediate repeater station, or one intermediate repeater set for each of the talking lines, is shown, between the center repeater station and either terminal station, a larger number of the same kind of intermediate repeater sets may be employed, in tandem, in any talking line, between the center station and each terminal station.

Associated with the repeater R_1 of line 2, at the west terminal repeater station, is a source 12 of control current of frequency f_1 . A similar source 13, of frequency f_2 , is associated with the east terminal repeater R_5 of line 2. Likewise, sources 14, 15, 16 and 17, of frequencies f_3 , f_4 , f_7 and f_8 , respectively, are associated with the terminal repeaters R_6 , R_{10} , R_{11} , and R_{15} , respectively. The sources 12, 14 and 16 are connected to west terminal control channel 20 and through that channel to the west end of line 1, band pass filters 21, 22 and 23 for passing frequencies f_1 , f_3 , and f_7 , respectively, being connected between the sources 12, 14 and 16, respectively, and the channel 20. The designation BPF, wherever occurring in drawing, indicates a band pass filter. Similarly, the sources 13, 15 and 17 are connected to east terminal control channel 24 and the east end of line 1 through band pass filters 25, 26 and 27 for passing frequencies f_2 , f_4 , and f_8 , respectively. The sources 12 to 17 are normally short-circuited, however, with respect to the filters 21 to 23 and 25 to 27 so that in the absence of speech transmission in the system no control impulses are sent over line 1. The band pass filters 21 to 23 and 25 to 27, and also the other band pass filters referred to

hereinafter, may be, for example, of the type disclosed in U. S. patent to G. A. Campbell, 1,227,113, May 22, 1917.

At the control current repeater set R_{16} , 5 band pass filters 30 and 31 select for eastwardly pointed amplifier 32 a group of frequencies including f_1 , f_3 , f_7 , and any other control frequencies to be transmitted eastward if such other frequencies are present in 10 line 1 by reason of line 1 being employed to control talking lines, not shown, other than 2, 3 and 4. Similarly, at repeater set R_{16} , band filters 33 and 34 select for westwardly pointed amplifier 35 a group of frequencies including f_2 , f_4 , f_8 , and any other control frequencies to be transmitted westward over line 1. Thus, these four filters are grouping filters for accomplishing frequency separation of the eastwardly directed 20 group of control frequencies from the westwardly directed group. At the repeater set R_{16} there are also means, for instance, tuned loops 36 to 43, for suppressing each control frequency in the westwardly directed group 25 of such frequencies, each of the tuned loops suppressing one of those frequencies. However, short circuits for the tuned loops are provided through the back contacts of relays F, 127 and I_2 at the repeaters R_2 , R_7 , 30 and R_{12} , respectively, so that in order for one of these tuned loops to be effective to suppress a control frequency it is necessary that the corresponding relay be operated to remove the short circuit from that loop.

35 At the control current repeater set R_{17} , band pass filters 45 and 46 select for amplifier 47 the group of frequencies passed by filters 30 and 31 of repeater set R_{16} , and band filters 49 and 48 select for amplifier 50 the group of frequencies which filters 33 40 and 34 at repeater set R_{16} , pass. At the repeater set R_{17} there are also tuned loops 56 to 63 which correspond in structure and function to the loops 36 to 53, respectively at repeater set R_{16} . Moreover, at the repeater set 45 R_{17} are also similar loops 66 to 73, for suppressing each control frequency in the eastwardly directed group of such frequencies, each loop suppressing one frequency. Short 50 circuits for the loops 66 to 73, as well as short circuits for the loops 56 to 63, are provided, through the back contacts of relays F, 132 and 133, and I_3 at the repeaters R_2 , R_8 , and R_{13} , respectively, so that in order for one of 55 these tuned loops to be effective to suppress a control frequency it is necessary that the corresponding relay be operated to remove the short circuit from that loop.

At the control current repeater set R_{18} , 60 are band pass filters 75, 76, 77 and 78 for accomplishing frequency separation of the control frequencies to be amplified by eastwardly pointed amplifier 79 from those to be amplified by the westwardly pointed amplifier 80, and also tuned loops 86 to 93,

corresponding in structure and function to the loops 66 to 73, respectively, of repeater set R_{17} .

At the east terminal repeater station are band filters 94, 95 and 96 for selecting the 70 frequencies f_1 , f_3 , and f_7 , respectively, and transmitting them to amplifier-rectifiers 97, 98 and 99, respectively, for controlling relays as described hereinafter. These amplifier-rectifiers and also the others referred to herein, may be, for instance, of the type disclosed in U. S. patent to E. D. Johnson 1,526,550, February 17, 1925 or of the type disclosed in my application Serial No. 667,437, filed October 9, 1923, entitled "Electric current 80 transmission."

At the west terminal repeater station are band pass filters 101, 102 and 103 for selecting the frequencies f_2 , f_4 , and f_8 , respectively, and transmitting them to amplifier-rectifiers 85 104, 105 and 106, respectively, for controlling relays as described hereinafter.

At the repeater set R_2 is a receiving set 110 to select from the frequencies transmitted through the amplifier 32 the frequency f_1 , for controlling relays A2, B2 and E at the repeater set R_2 . The designation Rf_1 , or Rf_2 , etc., wherever occurring in the drawing, indicates a receiving set for frequency f_1 or f_2 , etc. This receiving set should include a selective circuit, such as a series tuned circuit (not shown) resonant to f_1 or a band pass filter (not shown) for passing f_1 , and an amplifier-rectifier (not shown) for converting the control of frequency f_1 100 into direct current for operating the relays A2, B2 and E. Also at the repeater set R_2 , is a receiving set 111 to select from the frequencies transmitted through the amplifier 35 the frequency f_2 , for controlling relays 105 C2, D2 and F at repeater set R_2 . This receiving set, and also the others referred to hereinafter, may be like the receiving set 110, except that the frequency selected is not the same in all cases.

At the repeater set R_3 is a receiving set 115 to select from the frequencies transmitted through the amplifier 47 the frequency f_1 , for controlling relays A3, B3 and one of the F relays at the repeater set R_3 . 115 This receiving set is like the receiving set 110 just described. At the repeater set R_3 is also a receiving set 116, to select from the frequencies transmitted through the amplifier 50 the frequency f_2 , for controlling relays C3, D3 and the other F relay at the repeater set R_3 . This receiving set is like the receiving set 111.

At the repeater set R_4 is a receiving set 120 to select from the frequencies transmitted 125 through the amplifier 79 the frequency f_1 , for controlling relays A4, B4 and F at the repeater R_4 , this receiving set being like the receiving set 110. At the repeater set R_4 is also a receiving set 121, to select from the 130

6 frequencies transmitted through the amplifier 80 the frequency f_2 , for controlling relays C4, D4 and E at the repeater set R₄, this receiving set being like the receiving

5 set 111.

At the repeater set R₇ is a receiving set 125 to select from the frequencies transmitted through the amplifier 32 the frequency f_3 , for controlling relay G₁ at the repeater set 10 R₇; and at this repeater is also a receiving set 126 for selecting from the frequencies transmitted through the amplifier 35 the frequency f_4 , for controlling relays H₁ and 127 at this repeater set.

15 Similarly, at the repeater set R₈, receiving set 130 selects frequency f_3 to control relays G₂ and 132; and receiving set 131 selects frequency f_4 to control relays H₂ and 133.

Similarly, at repeater set R₉, receiving set 20 135 selects frequency f_3 to control relays G₃ and 137; and receiving set 136 selects frequency f_4 to control relay H₃.

At the repeater set R₁₂, receiving sets 140 and 141 select frequencies f_7 and f_8 , respectively, to control relays as described hereinafter. Similarly, at repeater set R₁₃ receiving sets 142 and 143 select frequencies f_7 and f_8 , respectively, and at repeater set R₁₄ receiving sets 144 and 145 select frequencies 30 f_7 and f_8 , respectively, to control relays as described hereinafter.

Subscribers' telephone sets 150, 151 and 152 connect with the repeater sets R₁, R₆ and R₁₁, respectively, by means of hybrid coils or 35 balanced three-winding transformers 153, 154 and 155, respectively, and impedance balancing networks 156, 157 and 158, respectively; and similarly, subscribers' telephone sets 160, 161 and 162 connect with the repeater sets R₅, R₁₀ and R₁₅, respectively, through hybrid coils 163, 164 and 165, respectively, and impedance balancing networks 166, 167 and 168, respectively. However, the balance between the networks and their 45 associated subscribers' loops may be only nominal.

The connection of the repeater sets R₁, R₆ and R₁₁ to the lines 2, 3 and 4, respectively, is by means of hybrid coils 170, 171 and 172, 50 respectively, and balancing networks 173, 174 and 175, respectively; and the connection of the repeater sets R₅, R₁₀ and R₁₅ to the lines 2, 3 and 4, respectively, is by means of hybrid coils 180, 181 and 182, respectively, and balancing networks 183, 184 and 185, respectively; but the balance between the networks and their associated toll lines may be only nominal.

60 Before describing the operation of the circuits of the system which involve tandem operation of repeater sets, the operation of individual repeater sets of the types involved will be described.

Considering the terminal, neutral type repeater set R₁, speech energy from the sub-

scriber's set 150 enters at the toll line terminals and passes to the input of eastwardly pointed repeater amplifier 200 by way of the bridge terminals of the hybrid coil 153. After amplification by amplifier 200, part of 70

this energy is transmitted through a delay circuit or path 202 and the hybrid coil 170, to the line 2; but a portion is taken by amplifier-rectifier 201 and operates relays A1 and B1. The designations DP and AR, 75 wherever occurring on the drawing, indicate a delay path and an amplifier-rectifier, respectively. The delay circuit or path 202

may be of any type suitable for producing the desired delay in the propagation of signals therethrough. The relay A1 opens a short circuit on the output of the delay circuit or path 202 for a sufficient interval and at the proper time to permit the transmission of each syllable of speech to the line 2

80 as it emerges from the delay circuit. The operation of relay B1, by opening a short circuit on the generator 12 of frequency f_1 , results in the transmission out upon the control line 1 of control impulses corresponding to each syllable of transmitted speech. The time of operation of this relay is so related to the time of lag introduced by the delay circuit that this control impulse precedes speech in reaching each of the repeater stations to the east of repeater set R₁ by a time sufficient for cutting the repeater in at that station. This time relation is maintained 85 all along the circuit so that each syllable finds each successive repeater cut in for it at the proper time. Preferably the delay time of the delay circuit is so related to the switching time of the relays that none of any syllable will be lost.

90 In the operation of this terminal repeater set R₁ on receiving speech energy delivered from the line 2 the hybrid coil 170 and control current of frequency f_2 which is delivered from the line 1 through the filter 101 and the amplifier-rectifier 104, relays C1 100 and D1 are operated by the control impulses, which are sent out preceding each syllable from the distant terminal station. There is, therefore no delay circuit required in the receiving branch of the circuit of the repeater 105 set, relay D1 opening in time to permit the passage of the received speech amplified by westwardly pointed repeater-amplifier 203, while relay C1 functions to prevent the operation of the relays A1 and B1.

110 In order to allow for transient reflection of received speech energy from the connected circuit 150, the contact shown as part of relay C1 should be arranged to be slow closing, for instance, by the use of a slow operated relay of the ordinary type or any suitable type as relay C1, or else the closing of the circuit extending through the contact should be delayed after those contacts close, for instance in the manner in which the closing 115 120

125 type as relay C1, or else the closing of the circuit extending through the contact should be delayed after those contacts close, for instance in the manner in which the closing 130

of the amplifier-rectifier circuit is delayed in my application Serial No. 667,437, referred to above.

The repeater sets R_5 , R_6 and R_{10} are the same type of neutral repeater set as the repeater set R_1 , and their operation will be apparent from the description just given of the operation of the repeater set R_1 . Their relays C_5 , A_6 and C_{10} correspond to the relay A_1 of set R_1 ; their relays D_5 , B_6 and D_{10} correspond to the relay B_1 of set R_1 ; their relays A_5 , C_6 and A_{10} correspond to the relay C_1 of set R_1 ; and their relays B_5 , D_6 and B_{10} correspond to the relay D_1 of set R_1 . The westwardly pointed repeater amplifier 210 or repeater set R_5 , the eastwardly pointed repeater amplifier 300 of set R_6 , and the westwardly pointed amplifier 310 of repeater set R_{10} , correspond to the eastwardly pointed repeater amplifier 200 of the sending branch of set R_1 ; the amplifier-rectifiers 211, 301 and 311 of repeater sets R_5 , R_6 and R_{10} , respectively, correspond to the amplifier-rectifier 201 in the sending branch of repeater set R_1 ; the delay circuits 212, 302 and 312 of repeater sets R_5 , R_6 , and R_{10} , respectively, correspond to the delay circuits of repeater set R_1 ; and the repeater amplifiers 213, 303 and 313 in the receiving branches of repeater sets R_5 , R_6 and R_{10} , respectively, correspond to the repeater amplifier 203 in the receiving branch of repeater set R_1 .

Considering now the operation of the intermediate neutral type repeater set R_2 , and assuming speech energy to be approaching the set over line 2 from the west, an impulse of frequency f_1 which just precedes it and reaches the repeater set R_2 over the control line 1 is amplified by the control circuit amplifier 32, selected by the receiving set 110, and operates relays A_2 and B_2 . The opening of the contacts of these relays arranges the connections of the single repeater amplifier 205 in the line 2 so that the amplifier will amplify from west to east in the line. At the end of the control impulse the repeater is again rendered inoperative to amplify in either direction in the line. Similarly, for speech in the direction from east to west, a control impulse of frequency f_2 opens the contacts C_2 and D_2 , rendering the same telephone repeater amplifier 205 operative to amplify from east to west in the line 2. Thus, the repeater set is normally in a neutral condition, waiting to be rendered operative to repeat in either direction, only one direction at a time, upon receiving a suitable control impulse for each syllable. The functions of relays E and F will be described hereinafter.

The repeater set R_4 is like the set R_2 , except that the relays E and F are operated by frequencies f_2 and f_1 instead of by f_1 and f_2 , respectively. The operation of R_4 will be

apparent from the description of the operation of R_2 and the description given hereinafter of the operation of line 2 as a whole. Repeater 209 corresponds to repeater 205 of set R_2 , and relays A_4 , B_4 , C_4 , D_4 , E and F correspond to relays A_2 , B_2 , C_2 , D_2 , E and F , respectively, of repeater set R_2 .

The repeater set R_3 is like the set R_2 , except that R_3 has two F relays and no E relay. The operation of R_3 will be apparent from the description of the operation of R_2 and the description given hereinafter of the operation of line 2 as a whole. Repeater 207 corresponds to repeater 205 of set R_2 , and relays A_3 , B_3 , C_3 and D_3 and F correspond to relays A_2 , B_2 , C_2 , D_2 and F , respectively, of the repeater set R_2 .

Considering now, the type of biased repeater set employed in line 3 at the center and intermediate repeater stations, repeater set R_7 comprises a single repeater amplifier 320, polarized switching relays 321 and 322 for reversing the pointing of repeater 320 in the circuit 3, control relays G_1 and H_1 responsive to control frequencies f_3 and f_4 , respectively, to control the switching relays, and relay 127 responsive to f_4 for a purpose which will be made apparent hereinafter. When an impulse f_3 , which should condition the repeater for amplifying from west to east in the circuit 3, energizes relay G_1 , the circuit through the left hand windings of relays 321 and 322 is opened, and the current flowing in the right hand windings through the contact of relay H_1 throws the armatures of relays 321 and 322 to the positions shown, so that repeater 320 will amplify from west to east in line 3. When the control impulse ceases and the contact of relay G_1 closes, the current in the left hand windings of relays 321 and 322 annuls the effect of the current in the right hand windings, but the armatures remain in the positions shown through the natural bias of the relays 321 and 322. They will remain in that position during and between all succeeding impulses of frequency f_1 . As soon as an impulse of frequency f_4 is received at the repeater set R_7 , however, the contact of relay H_1 is opened, and consequently the armatures of relays 321 and 322 are thrown to their other contacts, so that the repeater is conditioned to amplify from east to west in the line 3. It will remain in that condition until speech is again sent from the west toward the repeater. If desired, relays G_1 and H_1 may be so called vibrating relays, for instance, of the type disclosed in U. S. patent to S. G. Brown, 1,185,472, May 30, 1916, or U. S. patent to Ericsson and Dahlström, 1,169,387, January 25, 1916.

Repeater sets R_8 and R_9 are like set R_7 , except as regards relays 132 of set R_8 and relay 137 of set R_9 . The function of these relays will be developed later. The ele-

ments 330, 331, 332, G2 and H2 of set R_8 , and the elements 340, 341, 342, G3 and H3 of set R_9 , correspond respectively to elements 330, 331, 332, G1 and H1 of set R_7 .

5 Considering now, the type of biased repeater set employed in line 4, the repeater set R_{11} , for instance, has a single repeater amplifier 401, with a connection to its input side from the bridge points of the hybrid 10 coil 155 by means of a hybrid coil 402 and balancing network 403, a connection to its input side from the bridge points of the hybrid coil 172 by means of the hybrid coil 402 and balancing network 403, a connection 15 from its output side to the series winding of the hybrid coil 155 by means of a hybrid coil 404 and balancing network 405, and a connection from its output side to the series winding of the hybrid coil 172 by 20 means of the hybrid coil 404 and balancing network 405. The first of these connections includes a delay circuit 406 and may be short-circuited by the contact of a relay A_1 , or opened by means of the contact of a relay F_1 . The second of the four connections 25 may be short-circuited by the contact of a relay C_1 , or opened by means of the contact of a relay G_1 . The third connection may be short-circuited by means of the contact 30 of a relay D_1 , or opened by the contact of a relay H_1 . The fourth connection may be short-circuited by means of the contact of a relay B_1 , or opened by means of the contact of a relay E_1 . When the first and 35 fourth connections are effective, the repeater is pointed east; and when the second and third connections are effective, the repeater is in condition to amplify from the line 4 to the subscriber's loop 152. An amplifier-rectifier 407 controls certain of the relays 40 mentioned, in a manner which will be made apparent hereinafter; and relays J_1 and K_1 are provided for control purposes made apparent hereinafter. Relays A_1 , B_1 , C_1 and 45 D_1 are polarized, so that in the absence of any energizing current the armature of each relay remains as operated by one of the windings of that relay until the other winding of that relay is energized. The direction 50 in which each winding when energized tends to actuate an armature is indicated by an arrow on the drawing.

The other terminal repeater set for line 4, designated R_{15} , is similar to the set R_{11} , 55 relays C_5 , G_5 , F_5 and A_5 , of set R_{15} corresponding to the relays A_1 , F_1 , G_1 , and C_1 , respectively, of set R_{11} , relays B_5 , E_5 , H_5 and D_5 of set R_{15} , corresponding to the relays D_1 , H_1 , E_1 and B_1 , respectively, of set R_{11} , 60 repeater 441, hybrid coils 442 and 444 and networks 443 and 445 of set R_{15} corresponding to the repeater 401, coils 402 and 404 and networks 403 and 405 of set R_{11} , delay circuit 446 and amplifier rectifier 447 of set R_{15} 65 responding to delay circuit 406 and ampli-

fier-rectifier 407 of set R_{11} and relays J_2 and K_2 of set R_{15} corresponding to relays J_1 and K_1 , respectively, of set R_{11} .

The center repeater set R_{13} and the intermediate repeater sets R_{12} and R_{14} in the line 4 are similar to the terminal repeater sets as regards the repeater amplifiers and their connections in the line 4. The relays having their contacts in series or in short-circuiting relationship to those connections are 75 designated A, B, C, D, E, F, G and H relays in repeater sets R_{12} to R_{14} as in the case of repeaters R_{11} and R_{15} , but with subscripts 2, 3 and 4, in the case of the repeater sets R_{12} , R_{13} and R_{14} , respectively. In these three 80 sets the repeater amplifiers and the hybrid coils and balancing networks permanently connected to those amplifiers are designated the same as the corresponding elements in set R_{11} , except that the designating number is increased by 20 in the case of each of these elements for repeater sets R_{12} , by 30 in the case of each of the elements for repeater set R_{13} , and by 40 in the case of each of these elements for repeater set R_{14} . Hybrid coils 85 90 95 100 105 110 115 120 125 130

427 and 429 and balancing networks 428 and 430 of repeater set R_{12} , hybrid coils 437 and 439 and balancing networks 438 and 440 of repeater set R_{13} , and hybrid coils 447 and 449 and balancing networks 448 and 450 of repeater set R_{14} correspond to the hybrid coils 155 and 172 and balancing networks 158 and 175 of the repeater set R_{11} . The functions of relay I_2 in set R_{12} , relays I_3 in set R_{13} and relay I_4 in set R_{14} will be made apparent hereinafter.

In the operation of the neutral circuit comprising line 2 in transmitting from west to east, speech from the west, from telephone subset 150, will enter repeater set R_{11} , and after amplification by repeater amplifier 200 part of the energy is taken by the amplifier-rectifier 201 and operates the relays A_1 and B_1 . Relay A_1 opens a short circuit on the output of the delay circuit 202 to permit the transmission of each syllable of speech as it emerges from the delay circuit. It should be open a sufficient interval of time to permit the complete transmission of each syllable of speech, and as the time of transmission through the delay circuit is increased its release time should be lengthened to avoid clipping off the tail end of syllables. This lengthening may be accomplished by condenser 204 shown connected to be charged on closing of the relay contact. The opening of relay B_1 sends a control impulse from the generator 12 of frequency f_1 along the control line. As noted above, this control impulse will precede speech, on account of the time lag introduced by the delay circuit, in reaching each of the repeater stations to the east of repeater set R_{11} by a time sufficient to allow for cutting the repeater in at that station, this time relation being maintained 130

all along the circuit so that each syllable finds each successive repeater cut in circuit before it reaches it. On account of the delay circuit the control impulse should be 5 lengthened to prevent terminal clippings of syllables, by making the B1 relay slow releasing, for instance, by means of condenser 206 shown connected to be charged from the relay contact.

- 10 When the control impulse f_1 reaches the intermediate repeater station R_2 , it is amplified by repeater 32 for the control channels and after separation by receiving set 110 operates relays A2, B2 and E. The first 15 two relays cut the repeater 205 in circuit and the last breaks the output of the opposite control rectifier of receiving set 111 to the relays D2 and C2, but not to the F relay. The control impulse would continue along 20 the control channel and reaching the center repeater R_3 operate the A₃ and B₃ relays, cutting in the repeater 207, and open the F relay which controls the short circuit on loop 66 tuned to frequency f_2 and thereby prevents 25 transmission of F₂ through amplifier 50. Therefore, should an impulse of frequency f_2 come from the east after the repeater 207 has been thrown for speech transmission from west to east, it could do nothing. 30 If the repeater R_4 to the east of the center repeater is in neutral position when the control impulse f_1 arrives it will cut it in by operating relays A4 and B4 and prevent transmission of f_2 through amplifier 80 by 35 opening the F relay which controls a short circuit on loop 86 tuned to frequency f_2 . If a control impulse f_2 from the east gets to this station R_4 before f_1 it operates relays D4, C4 and E, the relays C4 and D4 pointing 40 the repeater 209 east to west, and the relay E interrupting the f_1 control of the A4 and B4 relays, but not of the F relay; now when f_1 comes a moment later it operates the F relay, thereby cutting off the input to the 45 D4, C4 and E relays and causing them to release, and thus permits the A4 and B4 relays to be operated to point repeater 209 from west to east and thus make transmission of speech from west to east possible. It 50 will be noted that the repeaters to the east of the center are under control of f_1 whether f_1 or f_2 reaches them first. The interlocking E relay at repeater set R_4 prevents the A4 and B4 relays from being simultaneously 55 operated with the D4 and C4 relays, which would permit the repeater 209 to sing. The E relay at repeater set R_2 similarly prevents repeater 205 from singing.
- When the control impulse f_1 reaches the 60 east terminal station it operates relays B5 and A5. The opening of the former permits speech transmission to the east through repeater amplifier 213. The opening of the latter stops speech and control energy transmission to the west.

The center repeater has two F relays; so that which ever control frequency gets there first controls the circuit. In the gaps between words coming from the west, part of control impulses f_2 from the east may get 70 by and reverse repeaters to the west of the center repeater R_3 . Interference between control impulses, due to such operation, should be guarded against. If the F relay, which stops the transmission of one control 75 frequency be given a relaxation time slightly greater than twice the time of transmission to the next repeater the combined operation of two neighboring stations will cut-off any interference from the control impulse that 80 has been trapped between two stations. This end can also be accomplished by giving relay B1 that much additional delay in releasing so that the additional length of the control impulses will hold any station operated for 85 a length of time equal to the time of transmission between stations after the next succeeding station has been properly operated. Condenser 208, shown connected to be charged from the contacts of the F relays 90 may be used to obtain the desired relaxation time for those relays, as the condensers correspondingly connected to the A1 and B1 relays serve to delay their closing.

After west or telephone set 150, gets 95 through talking the circuit remains locked up against a reply for the time of transmission in one section after his last word reaches east or telephone set 160. East can, therefore, break in only when west's pause 100 in speech is longer than the time of transmission of the circuit plus the time of transmission of one section, which latter time is the relaxation time of the terminal repeater. The operation of this circuit in 105 transmitting from east to west is similar to the operation just described for west to east transmission, and will be apparent without further description.

In the operation of the neutral-biased circuit comprising line 3, which circuit is shown biased from west to east, when west or telephone set 151 talks, it would operate, by control impulse f_3 , control relay G1 at the first intermediate repeater R_7 . The 110 opening of G1 would permit the polarized switching relays 321 and 322 to be thrown into the position shown. At the center repeater R_3 , the control impulse f_3 not only operates the control relay G2 but also prevents the transmission of f_4 by operating relay 132 which removes a short circuit from loop 67 tuned to frequency F₄. f_3 will repeat the same thing at the repeater station R_9 to the right of the center station if f_4 115 is not present. Now suppose f_4 reached the repeater R_9 before f_3 and by operating relay H3 threw the switching relay tongues to the right hand contacts, thereby pointing the repeater from east to west, f_3 coming shortly 120 125 130

later would by operation of the relay 187 open the short circuit about loop 87 tuned to frequency f_4 and thereby interrupt the transmission of f_4 , causing the H3 relay to 5 release; and the operation of the G3 control relay would cause the switching relays 341 and 342 to point the repeater from west to east. The operation of the circuit for east to west transmission is similar to the reverse 10 operation just described, and will be apparent without further description.

The biased type circuit comprising line 4 is shown biased from west to east. This biased circuit is distinguished by being operated by the opening of relay contacts. Considering the operation of the system for speech transmission from east to west, part of the energy coming from the hybrid coil 165 is taken by the amplifier-rectifier 447 20 and operates relays K₂, C₅, D₅, E₅, F₅, A₅, and B₅. The opening of K₂ removes a short circuit from the generator 162 of frequency f_8 and sends a control impulse along the control line 1. E₅ and F₅ should open a little 25 before C₅ and D₅ in order to prevent the repeater from singing when the latter two relays are opened. When A₅ and B₅ have been closed there is no necessity that relay contacts E₅ and F₅ should be open. Therefore 30 E₅ and F₅ should only stay open until the final make of A₅ and B₅, because when E₅ and F₅ are closed the repeater will be operative in the other direction on the opening of relay contacts instead of on the closing of 35 relay contacts. E₅ and F₅ are temporarily opened by the charging current of a condenser 460 that is placed in series with the relay windings; the relay windings and the condenser are shunted by a suitable resistance 461.

Continuing west from the east terminating repeater R₁₅ the control impulse f_8 on reaching the first intermediate repeater R₁₄ will operate the C₄, D₄, E₄, F₄, A₄ and B₄ 45 relays, thereby cutting the repeater R₁₄ in. At the center repeater R₁₃ it operates the C₃, D₃, E₃, F₃, A₃ and B₃ relays pointing the repeater from east to west, and also the I₃ relay, which removes a short circuit from 50 about the loop 58 tuned to frequency f_7 and thus prevents the transmission of the frequency f_7 from the other or east side. If f_8 reaches the repeater R₁₂ to the left of the center repeater before f_7 it will operate the 55 same series of relays as at the center repeater (C₂, D₂, E₂, F₂, A₂, B₂ and I₂). But if f_7 arrives at the repeater R₁₂ before f_8 it will operate the relays H₂ and G₂ (the A₂, B₂, D₂ and C₂ relays are already operated as 60 shown on the drawing). H₂ and G₂ are opened only for the time that it takes D₂ and C₂ to close. Now when f_8 arrives suppose H₂ and G₂ have had time to close. f_8 65 will interrupt the transmission of f_7 by operating I₂ to remove a short circuit from

about-loop 38 tuned to frequency f_7 . It will then prevent the repeater from singing while A₂ and B₂ are being closed by opening E₂ and F₂. The repeater would be cut in by operating C₂ and D₂. If H₂ and G₂ have not had time to close before the other relays are operated beginnings of words might be destroyed if the time delay in the delay circuit were not made long enough. Let us consider the worst possibility, viz. 75 G₂ and H₂ have just been operated when f_8 interrupts the transmission of f_7 by opening I₂. f_7 and f_8 must have met to the right of the repeater a distance the impulse traveled during one-half the time of break of relays 80 H₂ and G₂. The increased switching time of the repeater would then be equal to the time of make minus half the time of break of the H₂ or G₂ relays. If f_8 and f_7 meet just at the repeater H₂ and G₂ would not 85 have time to open before f_7 is interrupted by the opening of the I₂ relay. At the receiving terminal repeater f_8 besides pointing the repeater in the right direction breaks the input of the amplifier-rectifier supplying the 90 terminal relays for west.

The operation of this circuit in transmitting from west to east is similar to the operation described for transmitting from east to west, and will be apparent without further description. 95

The center repeater station, comprising the center repeater sets, is preferably located near the electrical center of the length of the talking circuits, as regards the propagation time required for the speech current energy to be transferred from one end of those circuits to the other end. 100

What is claimed is:

1. In combination, a plurality of translating devices, apparatus, including current transmission means having said translating devices distributed therealong, for controlling said translating devices over said means from each end of said means, and apparatus 105 controlled over said means from one end of said means for annulling control of certain of said devices which has been obtained through said means from the other end of said means.

2. A system comprising a plurality of repeater sets connected in tandem, means for pointing each set in either direction, and means responsive to transmission for controlling said first means and giving the 110 transmission in either direction complete control of the pointing of the repeaters even though while transmission in that direction is traversing the circuit transmission in the other direction causes one of the repeaters to 115 be pointed in said other direction. 120

3. In combination, a circuit, repeaters in tandem therein, including terminal repeaters and repeaters between said terminal repeater, means at each of said repeaters for control- 125 130

- ling the transmission efficiency of that repeater, means at one of said repeaters between said terminal repeaters for controlling said transmission efficiency controlling means 5 at another of said repeaters between said terminal repeaters, and means responsive to transmission to be repeated by said tandem connected repeaters for controlling said means at said one repeater. 10 4. In combination, a repeater circuit comprising a plurality of two-way repeater sets connected in tandem, means for conditioning each set for efficient transmission in only one direction at a time, means responsive to the 15 transmission to be repeated in either direction by said repeaters for controlling said first mentioned means, and means for giving the first started of two oppositely directed transmissions control over the circuit to the 20 exclusion of control by the second started transmission, when control of said first mentioned means through said second mentioned means has been partly obtained by said second started transmission before said first 25 started transmission has completed control of said first mentioned means by said second mentioned means. 5. The combination set forth in claim 4, in which said second mentioned means comprises means for transmitting control energy, 30 in each direction between points at the terminals of said circuit and said means for giving the first started transmission control over the circuit comprises means for causing 35 the control energy transmitted more than substantially half way between said points in one direction to annul the controlling action of control energy transmitted in the other direction. 40 6. The combination set forth in claim 4, in which said second mentioned means comprises means for transmitting control energy in each direction between points at the terminals of said circuit and said means for giving the first started transmission control 45 over the circuit comprises means for causing the control energy which reaches the repeater set nearest the center of the circuit first to stop transmission of oppositely directed control energy. 50 7. A circuit comprising neutral and biased types of two-way repeaters in tandem, each of said repeaters having means for conditioning the repeater for efficient transmission 55 in only one direction at a time, and means responsive to transmission to be repeated by said repeaters for controlling said first means. 60 8. A circuit comprising a two-way biased repeater and a two-way neutral repeater in tandem, each of said repeaters having means, controlled by the transmission to be repeated, for conditioning the repeater for efficient transmission in only one direction at a time. 65 9. A circuit comprising two terminal repeater sets of neutral type and another repeater set of biased type in tandem, each of said terminal sets having means for pointing that set in either direction in the circuit, said other set comprising means of different character for pointing said other set in either direction in the circuit, and means responsive to transmission to be repeated by said repeaters for controlling said means for pointing the terminal sets and the other set. 70 10. An electric wave transmission system comprising a signaling channel extending between two terminal stations and a repeated control channel extending between said stations, said signaling channel comprising 75 terminal repeater sets and other repeater sets in tandem, means at each of said signaling channel repeater sets for pointing the set in either direction in the channel, and means at each of said terminal stations responsive to the signaling energy at that station for sending control energy from that station over said control channel to each of said pointing means. 11. A system according to claim 10, in 80 which the means at the terminal stations for sending control energy over the control channel employ currents of distinctive frequencies for carrying the control energy 85 over the control channel. 12. A system comprising a signaling channel, a control channel, translating devices in said signaling channel, means at each of said devices for controlling that device, a source of control energy at each end of said 90 control channel, means at each terminal of the signaling channel, responsive to the signals sent from that terminal toward the other terminal for sending control energy 95 from one of said sources over control channel to said means at said devices, and means for delaying the transmission to each of said devices of signaling energy with respect to the control energy sent in response to that signaling energy. 100 13. In combination, a circuit, a repeater comprising means responsive to transmission in said circuit to be repeated in one direction for conditioning the repeater for efficient transmission in that direction, means for delaying the passage of transmission through the repeater in said direction with respect to the passage of said transmission to said transmission responsive means, means for conditioning the repeater for efficient 105 transmission in said circuit in the opposite direction, and means responsive to said transmission in said circuit in said opposite direction at a point remote from the repeater for controlling the third mentioned means. 110 14. A signaling system comprising a signaling channel, repeaters connected in tandem in said channel, a control current channel, means for conditioning each of said 115 repeaters for efficient transmission of sig- 120 130

nals in one direction only at a time, and means responsive to said signals for controlling said first means over said control current channel from each end of said signaling channel.

15. A system comprising a signaling channel, a separate control channel, translating devices in said signaling channel, means at each of said devices for controlling that device, a source of control energy at each end of said control channel, and means at each

terminal of the signaling channel, responsive to the signals sent from that terminal toward the other terminal for sending control energy from one of said sources over said control channel to said means at said devices. 15

16. A system in accordance with claim 15, in which the sources of control energy are of different frequencies.

In witness whereof, I hereunto subscribe 20
my name this 31st day of August, A. D. 1925.

ROBERT C. MATHES.
